(57) **CLAIM**

The ornamental design for the golf ball slider weight for golf club, as shown and described.

DESCRIPTION

FIG. 1 is a view of my golf ball slider weight residing in the immediate vicinity of the handle of the golf club;
FIG. 2 is a view showing a golf ball slider weight having moved down the shaft to a location adjacent the club head; and,

FIG. 3 is a view looking through the golf ball slider weight, when removed from the shaft of the golf club.
The broken line showing is for illustrative purposes only and forms no part of the claimed design.
